W. F. COSTELLO,
HORSE COLLAR AND SWEAT PAD,
APPLICATION FILED APR. 20, 1914.

1,111,218.

Patented Sept. 22, 1914.

UNITED STATES PATENT OFFICE.

WILLIAM F. COSTELLO, OF SAN ANTONIO, TEXAS.

HORSE-COLLAR AND SWEAT-PAD.

1,111,218.

Specification of Letters Patent. Patented Sept. 22, 1914.

Application filed April 23, 1914. Serial No. 833,304.

To all whom it may concern:

Be it known that I, WILLIAM F. COSTELLO, a citizen of the United States, residing at San Antonio, in the county of Bexar and State of Texas, have invented a new and useful Horse-Collar and Sweat-Pad, of which the following is a specification:

This invention relates to certain new and useful improvements in collars for horses and more particularly to one which contemplates the combining of a sweat pad with a collar in a novel and advantageous manner.

The object of the present invention is to provide a device of the class mentioned, in which the sweat pad will be held against balling up and in which the means whereby the pad is held in position will materially strengthen and reinforce the collar.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawing accompanying this specification and forming a part thereof, the preferable form of my invention has been illustrated, in which:

Figure 1 is a view in perspective of my improved collar and sweat pad. Fig. 2 is a cross-sectional view taken on the line 2-2 of Fig. 1.

Referring to the drawings in which similar reference numerals designate corresponding parts throughout the several views, the body portion 3 of the collar is formed of a continuous strip of leather, duck, or allied material and is stuffed, so as to maintain its shape, with the material 4. The edges 45 of the material of which the collar is formed are indicated at 5 at which juncture they overlap some little distance, allowing for their proper and efficacious securing. The collar is provided with or includes the usual 50 rim 6 and to the line of demarcation between the rim and body portion of the collar is sewed the reinforcing strip 7. The strip is formed of leather or allied textile material and extends entirely around the rim, 55 being sewed at one extremity 8 to the outer juncture of the rim and collar and at its inner

extremity extends beneath the one extremity 9 of a sweat pad. A sweat pad 10 extends over and is spaced a distance from the inner wall 11 of the body portion of the collar and is sewed to the outer extremity 5 thereof by the stitching 12. The sweat pad extends around the outer rim or extension 5 as indicated at 13 and the stitching by means of which it is secured to the collar extends through the three layers of material as indicated in Fig. 2. In order to hold the extremity 9 to the collar, the stitching 14 is employed, the same extending through two layers of the collar rim, the two layers of the reinforcing strip 7 and through the sweat pad extremity 9.

The foregoing provides that a substantially continuous surface will be provided between the rim and sweat pad and that furthermore the entire structure will be reinforced and suitably braced at those points at which the greatest wear is likely to occur.

The two extremities of the collar are reinforced by the end pieces 15, the same being formed of some semi-rigid and tough material and protecting the collar and pad from excessive wear at these points.

The pad 10 is formed of some suitable absorbent material and beneath which the hair or allied stuffing material 16 is placed.

The combined pad and collar as thus formed is efficient in use and should the pad become worn through, the device may still be used with more or less success due to the wall 11 of the collar, until such time as a new device can be procured or the device in question mended or renovated.

Having thus described my invention, what I claim to be new is:

1. An article of the class described, comprising a collar with a body portion and rim, a sweat pad extending over the outer surface of the body portion, a reinforcing strip embracing the rim and disposed beneath the extremity of the sweat pad, stuffing material interposed between the sweat pad and collar and stitching extending through the sweat pad, reinforcing band, and rim, and holding the same in fixed relation.

2. The combination with a horse collar including a body portion and outstanding rim, of a sweat pad secured thereto and extending over the outer surface thereof, and a reinforcing band encompassing the rim and extending beyond the line of demarcation

thereof, said reinforcing band terminating beneath said sweat pad and beyond said rim and stitched to the former, the opposite extremity of said sweat pad projecting around 5 the outlying extremity of the body portion and stitched thereto.

3. An article of the class described, comprising a substantially ovate-acuminate body portion, a rim at one extremity thereof, an outstanding projection at the other extremity formed by the sewing together of the extremities of the material of which the body portion is formed, a sweat pad extending over the outer surface of the said 15 body portion, one extremity of the sweat pad projecting beyond the line of demarcation

of the rim and the opposite extremity extending over the said body portion extension and stitched or sewed thereto, and a reinforcing band embracing the rim and 20 projecting beneath the sweat pad, and stitching extending through the sweat pad, reinforcing band, and the rim, and holding the same in fixed relation.

In testimony that I claim the foregoing 25 as my own, I have hereto affixed my signature in the presence of two witnesses.

WILLIAM F. COSTELLO.

Witnesses:

FORREST CAMPBELL,
GEO. M. MAYER.
